UNITED STATES PATENT OFFICE.

YOZAYEMON HARADA, OF MOUNTAIN VIEW, CALIFORNIA.

AUTOMOBILE SIGNAL.

Application filed March 7, 1924. Serial No. 697,525.

My invention relates to a device for mounting upon an automobile whereby the driver thereof may indicate to the drivers of other machines and to pedestrians the course he is going to pursue; that is whether he is going to continue to drive straight ahead, or turn to right or left, or stop.

It is the object of my invention to provide a device of the character indicated that will be positive in action, highly efficient in its practical application, capable of being rendered visible by day and night, compact in form and simple in construction and operation.

15 In the drawing:

Figure 1 is a side elevation of the complete device in position on an automobile, part of the latter broken away.

20 Figure 2 is a rear elevation of a portion of the device, greatly enlarged.

Figure 3 is a side elevation of the view in Figure 2.

Figure 4 is a section through the signal element on line 4—4 of Figure 2.

25 Figure 5 is an enlarged side elevation of that portion of the device used for operating the signal arm.

Figure 6 is an enlarged elevation of the handle and locking mechanism for the same.

30 Referring more particularly to the drawing, I show at 1 a case arranged in a vertical plane and mounted on the edge of a wind-shield 2 by means of clamps 3, and consequently lying in the plane of the wind-shield 35 with its outer edge open as at 4. The bottom of case 1 is circular in formation with a widened portion as at 5 fitted with a hinged door 6 normally held closed by catch 7. Along the axis of portion 5 is mounted a 40 fixed pin or stub shaft 8.

On shaft 8 is revolutely mounted a signal element 9 having colored glass windows 10—10 in its two sides and having an electric light bulb 11 arranged therein as shown.

45 This bulb is fitted with wires 12—13 terminating in bosses 14—15 on the exterior of circular portion 5 and insulated therefrom.

On the inner surface of case 1 are arranged two arcuate contact strips 16—17 50 having their terminals 18—19 connected to the opposite poles of a battery as at 20. The strips are so arranged that when the element 9 is rotated on its axis into any of the positions 21—22—23 the terminals 14—15 will engage strips 16—17 thereby closing the

electrical circuit and causing the bulb to light.

Signal element 9 carries a hub 24 having a coiled spring 25 engaging the side thereof as at 26 and the stationary shaft 8 whereby to normally maintain the element 9 encased in casing 1 as shown. In groove 27 formed in the perimeter of hub 24 is positioned a cable 28 passing through an orifice 29 in case 1 and through a flexible conduit 30 to an 65 operating mechanism indicated at 31.

The operating mechanism consists of an annular case 32 arranged in a vertical plane and mounted upon the steering post of an automobile by means of a rod 33 and clamp 70 34. The case 32 has a slot 35 formed in the upper portion of its perimeter and has a portion of one side hinged as at 36 and normally held in a closed position by a catch at 37.

Within case 32 and fixedly mounted 75 on rod 33 is an arcuate element 38 provided with spaced notches 39—40—41—42. Revolu-

ably mounted on rod 33 within said case 32 and projecting through slot 35 therein is a handle 43 having a rod 44 slidably 80 mounted therein and normally held in an extended position by spring 45. Pivottally mounted on handle 43 is a catch 46 arranged to engage one of said slots 39—40—41—42 at one end and pivotally connected to rod 44 85 at the other end.

The result of this construction is that the handle 43 is normally held in one position by the engagement of catch 46 with slot 39. By pressing upon rods 44 the catch is thrown out of engagement with slot 39 and the handle swung forward until the catch engages slot 40 and so on. The cable 28 being brought around the under side of rod 33 and attached to handle 43 it necessarily follows that with the cable 90 properly adjusted a movement of the handle from slot 39 to slot 40 will move the signal 9 from its position in the case 1 to position 21 (turn right). Moving handle 43 from slot 40 to slot 41 will move the 100 signal from position 21 to position 22 (turn left). Moving handle 43 from slot 41 to slot 42 will move the signal from position 22 to position 23 (stop).

Upon moving the handle 43 clear back 105 to slot 39 the spring 25 will swing the signal about shaft 8 back into its normal position in casing 1.

As heretofore described, the signal element will be lighted up from within all of 110

the time it is out of case 1, giving a clear warning from both front and rear of the machine.

It is to be understood, of course, that changes in construction and mode of operation may be made within the scope of the appended claim.

I claim:

10 A signal device comprising a case adapted to be mounted upon an automobile, a signal element pivotally mounted in said case, resilient means for urging said element into said case, and manually operated mechanism

for forcing said element out of said case, said case having a circular lower portion of greater width than the upper portion and having a closure therefor, a shaft axially positioned in said circular portion and on which the signal element is mounted, a hub formed on said signal element in concentric relation to said axis and within the circular portion of said case and to which said resilient means and said manually operated mechanism are connected. 15 20
